UNITED STATES PATENT OFFICE.

FRED L. DAGGETT, OF MARION, MASSACHUSETTS.

PACKAGING AND DISPLAY BOX.

Application filed June 17, 1921. Serial No. 478,402.

To all whom it may concern:

Be it known that I, FRED L. DAGGETT, a citizen of the United States, and a resident of Marion, county of Plymouth, and State 5 of Massachusetts, have invented an Improvement in a Packaging and Display Box, of which the following description, in connection with the accompanying drawings, is a specification, like characters on the drawings representing like parts.

My invention relates to packaging and displaying articles and particularly but not exclusively to a box for holding confections for shipment and for displaying them for 15 vending.

My invention will be best understood from the following specification when read in light of the accompanying drawings of a specific embodiment of my invention selected for illustrative purposes, while the 20 scope of my invention will be particularly pointed out in the appended claims.

In the drawings:—

Fig. 1 is a section of the submitted embodiment of my invention;

Fig. 2 is a perspective according to Fig. 1 with parts broken away and parts omitted;

Fig. 3 is a perspective of one of the trays; 25 and

Fig. 4 is a plan of one of the clips for holding the display card in position.

Referring to the drawings, I employ a box having the side walls 1 and 2 and the bottom 3, this box being constructed of cardboard or other suitable material. As illustrated in Figs. 1 and 2 of the drawings at opposite ends of the box I provide a channel-shaped member comprising the flanges 4 and webs 5, said member being of any suitable material, for example, constructed of a cardboard strip having down-turned end portions to provide the flanges, the latter resting on the bottom of the box and being of such height as to support the web in spaced relation to the upper edges of the side walls of the box.

The channel-shaped members are adapted to support a layer of confections or other articles in proximity to the top of the box and although these articles may be placed directly upon the webs 5 I preferably provide for this purpose one or more trays 6. These trays I may construct of cardboard or other suitable material and may provide them with an easel support, shown by the

drawings in the form of a strip of cardboard or other flexible material, a portion 7 of which is glued or otherwise secured to the bottom of the tray in order that the strip may be bent to cause the portion 8 thereof to form the leg of the easel support. Normally the leg 8 will lie against the bottom of the tray.

In practice, the trays may be first packed with the confections *a*, each of which may be provided with the ornamental jacket 9 and the trays and box then placed on the weighing scales and the bulk of the contents to be shipped then placed in layers on the bottom of the box until a predetermined, measured quantity of confections is packed. Over each layer is placed a cardboard or a like sheet 10. On the uppermost sheet 10 I place a filler 11 of paper or the like and then insert the channel-shaped members and on the latter place the trays. When the lid (not shown) of the box is placed in position, the contents of the trays are firmly held in position and the trays together with the channel-shaped members and filler 11 hold the confections in the bottom of the box in position to prevent displacement of the latter during shipment. It will be understood that if desired but one tray and channel-shaped member may be employed and a filler similar to the filler 11 substituted for the omitted tray.

In vending the contents of the box, the box is placed on a counter or in a show-case with the tray at the front of the box in elevated position as shown by Fig. 1. The rearward tray, if it is used, may then be removed and its contents vended after which the rearward channel-shaped member may be removed together with the filler and cardboard strips 10 to permit removal of the bulk of the contents at the bottom of the box. It will be noted that the articles in the tray 5 present for display purposes a sample of the contents of the box and obscure from view the more or less disordered contents of the remainder of the box.

If desired I may provide one of the edges of the tray at the front of the box with a fastening means for holding a display card 12. In the submitted embodiment of my invention, for this purpose I have shown a clip formed of wire bent to provide the overlapping arcual portions 13 and 14 and the points 15 and 16. In an obvious manner the points 15 and 16 may be forced over the

edge of the tray to cause said edge to be gripped by the opposite portions 13 and 14, after which the card may be placed between the edge of the tray and the arcual portion 13.

Although I have described one specific embodiment of my invention for purposes of illustration it is to be understood that I am not limited thereby to its particular details, materials, arrangement and number of parts but that wide deviations may be made therefrom without departing from the spirit of my invention.

Claims.

15. 1. The combination with a box for packaging and displaying articles of a channel-shaped member having flanges adapted to rest on the bottom of the box adjacent the sides thereof and having a web supported by said flanges in spaced relation to the top and bottom of the box, and said channel-shaped member being of length less than the corresponding dimension of said box whereby articles may be removed from the bottom

of the box without disturbing the articles supported on said web.

2. The combination with a box of a tray of less length than said box located at one end of said box, a member supporting said tray having down-turned end portions at 30 the sides of said box and resting on the bottom of said box, and an easel support for said tray adapted to rest on said member.

3. The combination with a box for packaging and displaying articles, of a pair of 35 channel shaped members having flanges adapted to rest on the bottom of said box adjacent the sides thereof and having webs supported by said flanges in spaced relation to the top and bottom of said box, one of 40 said channel shaped members being removable from said box, said channel shaped members being of length less than the corresponding dimension of said box, and trays supported on said webs.

In testimony whereof, I have signed my name to this specification.

FRED L. DAGGETT.
